UNITED STATES PATENT OFFICE.

WILLIAM H. GEORGE, OF DEXTER, IOWA.

DRIVING MECHANISM FOR WASHING-MACHINES.

965,811.

Specification of Letters Patent. Patented July 26, 1910.

Application filed October 8, 1908. Serial No. 457,181.

To all whom it may concern:

Be it known that I, WILLIAM H. GEORGE, a citizen of the United States of America, and resident of Dexter, Dallas county, Iowa, have invented a new and useful Driving Mechanism for Washing-Machines, of which the following is a specification.

The object of this invention is to provide improved means for operating the rubbing mechanism of a washing-machine.

A further object of this invention is to provide improved means for gearing a balance-wheel to the rubbing mechanism of a washing-machine.

My invention consists in the construction, arrangement and combination of elements hereinafter set forth, pointed out in my claims and illustrated by the accompanying drawing, in which:

Figure 1 is a side elevation of the machine. Fig. 2 is an elevation of the machine at right angles to Fig. 1. Fig. 3 is a plan of the machine. Fig. 4 is a bottom plan of the machine.

In the construction of the machine as shown, the numeral 10 designates a containing vessel or tub, which may be of any desired form and construction, and provided with a hinged cover 11. An agitator is mounted on the lower end portion of a shaft 12 vertically positioned in and extending through the center of the cover 11; and a pinion 13 is mounted rigidly on the upper end portion of said shaft above said cover.

A bearing-plate 14 is fixed to the central portion of the bottom 15 of the tub 10, and, extending radially thereof, projects at one end beyond the wall of said tub. A lever 16 is fulcrumed near its lower end in a bearing 17 formed on the outwardly projecting end portion of the plate 14, and said lever occupies an upright position normally. A lever 18 is fulcrumed at its center on a bearing 19 fixed to and projecting horizontally from the wall of the tub 10 diametrically opposite the lever 16. The lever 18 normally occupies an upright position and is spaced apart from the wall of the tub. The lever 18 has its end portions curved outwardly relative to the wall of the tub, and the upper end of said lever is hinged to one end portion of a pitman 20. The pitman 20 is formed with a rack 21 on its inner end portion, adapted to mesh with the pinion 13, and a roller 22 is pivoted on the cover 11 and engages the outer face of the

pitman to hold the rack in mesh. A pitman 23 pivotally connects the lower end portions of the levers 16 and 18 and extends diametrically of the bottom 15 of the tub. A shaft 24 is journaled in a bearing 25 formed on the plate 14 adjacent the center of the bottom 15, and also is journaled in a bearing 26 fixed to said bottom adjacent the rim thereof. The shaft 24 extends transversely of the tub approximately at right angles to the pitman 23. A pinion 27 of relatively small diameter is mounted rigidly on the inner end portion of the shaft 24 and meshes with a spur gear 28 of relatively large diameter, which spur gear is mounted on a stub axle 29 carried by a bearing 30 formed on and extending downward from the plate 14. The spur gear 28 is located adjacent the pitman 23, and the axis thereof is parallel with the axis of the shaft 24. A wrist-pin 31 is mounted on the spur gear 28, and a pitman 32 connects said wrist-pin to the lower end portion of the lever 16. The pitmen 23 and 32 are on opposite sides of the lever 16 and spur gear 28 and have a common point of articulation on said lever.

Suitable means may be employed to latch the cover 11 to the tub, and I show these means in conventional form and designated by the numeral 33. Suitable handles 34 may be applied at any desired points to the wall of the tub, whereby the tub may be carried about and positioned as desired.

In practical use, the clothing to be washed is placed in the tub 10 and the cover is closed and latched in such manner as to hold the agitator in contact with the clothing. Then the rack 21 is caused to mesh with the pinion 13 and manual force is applied to the upper end portion of the lever 16 to oscillate said lever. The lever 16 acts through the pitman 23 to oscillate the lever 18, and the latter lever rectilinearly reciprocates the pitman 20 and rack 21 to the rotation of the pinion 13, shaft 12 and agitator. The lever 16 acts through the pitman 32 and wrist-wheel 31 to the rotation of the spur gear 28, and said spur gear rotates the pinion 27 and shaft 24 at increased speed. The motion of the shaft 24 is made uniform and maintained by momentum of the balance-wheel 35 mounted on the outer end portion of said shaft.

I claim as my invention:

1. A driving mechanism for washing machines, comprising a suitable support, a de-

110

vice to be driven on said support, a hand lever fulcrumed on said support, a connecting lever fulcrumed on said support, a pitman connecting said levers, a rack connecting the latter lever to the device to be driven, a balance-wheel and gearing on said support, and a pitman connecting the hand lever to said gearing.

2. A driving mechanism for washing machines, comprising a suitable support, a device to be driven on said support, a hand lever fulcrumed on said support, a connecting lever fulcrumed on the opposite side of said support from said hand lever, said levers arranged for oscillation on horizontal parallel axes, a pitman connecting the lower ends of said levers, and a rack connecting the upper end of the connecting lever and the device to be driven.
3. A driving mechanism for washing machines, comprising a device to be driven, a lever mounted for oscillation, a rack connecting said lever and device to be driven, a hand lever mounted opposite the first lever, a pitman connecting said levers, a speed-increasing train of gearing, a balance-wheel connected to the terminal gear of the train, and a pitman connecting the initial gear of the train to the hand-lever.
4. A driving mechanism for washing machines, comprising a suitable support, a shaft mounted in the top thereof in a vertical plane, a pinion on the upper end of said shaft, a rack in mesh with said pinion, a lever mounted vertically on one side of said support and hinged at its upper end to said

rack, a hand-lever mounted in vertical position on the side of said support opposite to the first lever, a pitman connecting the lower ends of said levers and extending transversely of and beneath said support, a speed-increasing train of gearing beneath said support, a balance-wheel connected to the terminal gear of the train, and a driving pitman connecting the hand lever to said train of gearing.

5. A driving mechanism for washing machines, comprising a suitable support, a device to be driven on said support, a hand lever fulcrumed on said support, a connecting lever fulcrumed on the opposite side of said support from said hand lever, said levers arranged for oscillation on horizontal parallel axes, a pitman connecting the lower ends of said levers, a rack connecting the upper end of the connecting lever and the device to be driven, a horizontal counter shaft on said support between the lower ends of said levers, a gear on one end portion of said counter shaft and a balance wheel on the opposite end portion of said counter shaft outside the support, a spur gear pivotally mounted on the support and meshing with the first gear, and a pitman connecting the lower end portion of the hand lever to said spur gear.

Signed by me at Dexter, Iowa, this 22nd day of January, 1908.

WILLIAM H. GEORGE.
